UNITED STATES PATENT OFFICE

ALBERT SADACCA, OF NEW YORK, N. Y., ASSIGNOR TO NOMA ELECTRIC CORPORATION,
OF NEW YORK, N. Y., A CORPORATION OF NEW YORK

ELECTRIC-LIGHTING DEVICE

Application filed April 5, 1928. Serial No. 267,522.

This invention relates to electric lighting devices and portable decorative lighting sets such as Christmas tree lighting outfits.

Among the objects of the invention is its provision of a device of the character described which shall comprise few and simple parts, form a highly artistic lighting unit, comparatively cheap to manufacture and withal rugged in construction and practical and efficient to a high degree.

Other objects of this invention will in part be obvious and in part hereinafter pointed out.

The invention accordingly consists in the features of construction, combination of elements, and arrangement of parts which will be exemplified in the construction herein-after described, and of which the scope of application will be indicated in the following claims.

In the accompanying drawing, in which is shown one of the various possible illustrative embodiments of this invention.

Fig. 1 is a perspective view of a Christmas tree trimmed with an electric lighting outfit and a decorative unit embodying the invention.

Fig. 2 is a front elevational view of the improved Christmas tree lighting unit, partly in section to expose the interior construction.

Fig. 3 is a front elevational view of the improved Christmas tree lighting unit shown in mounted position, and

Fig. 4 is a fragmental view in side elevation of the mounting means portion of the device shown in Fig. 2.

Referring in detail to the drawing 10 denotes an electric lighting device embodying the invention, in the form of a lamp socket unit adapted to be attached to a portable decorative lighting set such as Christmas tree lighting outfits.

Although, as here shown, the invention may be incorporated in Christmas tree lighting sets or the like portable circuits, the device 10 forms a unit which may be detachably connected with such sets or circuits.

In Fig. 1, the Christmas tree 11 is shown trimmed with a portable lighting outfit 12,

which extends through the branches thereof, one or more of the screw receptacle outlets 12^a of said outfit being connected with one or more units 10 by means of a detachable plug 13 extending from the latter. Said plug may be of any well understood construction and has connected thereto the usual flexible conductor wires 14. The latter serve as a circuit extension between said plug 13 and a decorative fixture member 15 here shown of such structure as to simulate a candle when fitted with an electric bulb 16, as shown in Figs. 1 and 3.

The member 15 may comprise an elongated cylindrical shell or other form of tubing having an open end 15^a and is preferably made of relatively thin sheet metal. Said shell has an integral conical closure 15^b at the other end formed with a nipple 15^c aligned with the axis of the cylindrical shell member 15, said nipple extending outwardly from said closure and forming a passage wherethrough the conductor wires 14 pass from the plug 13 into said member. The ends of said conductor wires 14 opposite said plug, within said member 15 connect the centre and shell terminal contacts 17^a and 17^b respectively, of a screw receptacle outlet 17. Said outlet 17 is mounted concentrically within the member 15 at the said open end 15^a and is adapted to receive the bulb 16 as is shown in Fig. 2.

The receptacle outlet 17 extends within a bushing 18 made of any incombustible or fire-resistance electrical insulating material, such as a pheno-condensate product, fibre, or the like materials. A filler tubing 19 made of paper, card-board or other cheap material keeps the bushing 18 and outlet 17 spaced from the walls of the member 15.

When the member 15 is made of very thin sheet material, the tubing 19 preferably only partially fills the interior thereof to serve as a reinforcement to prevent said member from collapsing apart upon rough handling of the unit 10. The bushing 18 need be made only sufficiently long to shield the tubing 19 from possible exposure to arcing if the wiring extending through said tubing becomes defective.

A bead 20 is mounted for sliding movement on the conductor wires 14 between the member 15 and the plug 13.

The practical use of the invention will now 5 be clear.

After the parts are assembled as shown in Fig. 2, the plug 13 may be attached to any suitable outlet receptacle such as socket 12^a of a Christmas tree lighting outfit 12. A branch 10 of the tree or other support 21 is inserted between the conductor wires 14 adjacent the closure 15^a and the bead 20 is then slid up to clamp the support 21, as is clearly shown in Fig. 4. The unit 10 provided with a bulb 16 15 may thus be mounted with the member 15 in an upright position to simulate a candle while the flexible conductor wires 14 permit connecting the plug 13 to an outlet receptacle positioned in any angular relation with respect to 20 said member 15. Thus as shown in Fig. 1, for example, while the plug 13 extends horizontally the candle simulating unit 10 may by reason of the flexible connections intermediate the member 15 on the plug be adjusted in ordinary 25 vertical position and maintained in such position by the clamping action of the bead 20, thus giving the desired realistic effect. The outer surface of the member 15 is preferably finished with a pleasing ornamental decoration 30 which greatly adds to the artistic appearance of the unit 10.

It will thus be seen that there is provided a device in which the several objects of this invention are achieved, and which is well adapted 35 to meet the conditions of practical use.

As various possible embodiments might be made of the above invention, and as various changes might be made in the embodiment above set forth, it is to be understood that all 40 matter herein set forth or shown in the accompanying drawing is to be interpreted as illustrative and not in a limiting sense.

I claim:

45 1. A decorative lighting device of the character described simulating a candle comprising a tubular member having an open end, an integral closure for the other end of said member having a central opening therein, an insulating bushing, a filler piece surrounding said bushing, said bushing and piece being snugly fitted into the open end of said member to form a reinforcement for the latter, a receptacle outlet adapted to receive an electric bulb carried by said bushing, and flexible conductor wires connected to said outlet, said wires extending through said bushing member and the closure opening as and for the purpose described and specified.

60 2. A lighting device of the character described simulating a candle comprising a tubular shell member having an open end, a conical closure for the other end of said member having an opening extending axially with respect to the latter, an electrically insulating

and fire-resistant bushing, a receptacle outlet adapted to receive an electric bulb secured in said bushing, a filler piece of less fire-resistant properties than said bushing snugly fitted into the open end of said member, said piece supporting said bushing and outlet centrally within said member, and flexible conductor wires connected to said outlet extending through said bushing member and opening, said filler piece and bushing extending less than the entire length of said member, as and for the purpose described and specified.

In testimony whereof I affix my signature.

ALBERT SADACCA.
